Primary Examiner — Rashida Johnson(74) *Attorney, Agent, or Firm* — Kathryn E. Cox; Andrea E. Bates(57) **CLAIM**

What is claimed is the ornamental design for a wireless electric guitar, as shown and described.

DESCRIPTION

FIG. 1 is a perspective view of the front of the guitar.

FIG. 2 is a front view of the guitar;

FIG. 3 is a back view of the guitar;

FIG. 4 is a left side elevation view of the guitar;

FIG. 5 is a right side elevation view of the guitar;

FIG. 6 is an end view of the guitar taken from the neck of the guitar; and,

FIG. 7 is an end view of the guitar taken from the butt of the guitar.

The broken lines in FIGS. 1-7 represent the portions of the design, which form no part of the claim.
